United States Patent

Des. 238,070
Patented Dec. 16, 1975

238,070

COMBINED VANITY TOP AND BASIN

Richard J. Ganger, Los Angeles, Calif., assignor to
Dimensionetix, Inc.

Filed Oct. 4, 1974, Ser. No. 512,051

Term of patent 14 years

Int. Cl. D23—02

U.S. Cl. D23—58

Fig. 1.

Fig. 2.

Fig. 3.

Fig. 4.

FIG. 1 is a top plan view of a combined vanity top and basin showing my new design;

FIG. 2 is a front elevational view thereof;

FIG. 3 is a right side elevational view thereof, the left side being a mirror image of the right side shown; and

FIG. 4 is a cross-sectional view taken along line 4—4 of FIG. 1.

I claim:

The ornamental design for a combined vanity top and basin, substantially as shown and described.
